DAVID DALE, OF CHICAGO, ILLINOIS.

AIR-BRAKE-CONTROLLING MECHANISM FOR BLOCK-SIGNAL SYSTEMS.

1,113,814.

Specification of Letters Patent. Patented Oct. 13, 1914.

Application filed December 12, 1913. Serial No. 806,176.

To all whom it may concern:

Be it known that I, DAVID DALE, a citizen of the United States of America, and a resident of Chicago, in the county of Cook and State of Illinois, have invented certain new and useful Improvements in Air-Brake-Controlling Mechanisms for Block-Signal Systems, of which the following is a specification.

10 The main objects of this invention are to provide an improved form of automatic brake-controlling mechanism adapted to be electrically controlled for automatically setting the brakes of a railway car or train 15 when the same approaches a point of danger along the track such as an open switch, open draw or an occupied block; to provide a device of this kind particularly adapted for use in connection with air brake systems in 20 which the brakes are set through the opening of an air escape valve; to provide improved valve opening mechanism adapted when released to acquire considerable momentum before engaging the air escape valve 25 so that the initial engagement is in the nature of a blow; to provide valve releasing mechanism of this kind in which the valve is cammed to its open position at an increasing velocity after receiving the initial impulse; to provide improved locking means 30 for holding said valve releasing mechanism in its retracted position; to provide improved counter-locking mechanism for securing said locking mechanism against accidentally releasing said valve releasing mechanism, and to provide other means adapted to retract said counter-locking means in advance of the release of said valve 35 releasing mechanism by said locking means. 40 An illustrative embodiment of this invention is shown in the accompanying drawings, in which—

Figure 1 is a front elevation of the controlling mechanism, the valve being shown in section. Fig. 2 is a fragmentary view in elevation showing the position of the parts when the mechanism is released for causing the setting of the brakes. Fig. 3 is a fragmentary elevation of the mechanism, in the 45 position shown in Fig. 1 but with certain parts in front broken away. Fig. 4 is a detail as viewed from the plane of line A—A of Fig. 1. Fig. 5 is a fragmentary detail view partly sectional taken on the line B—B 50 of Fig. 1. Fig. 6 is an enlarged detail of 55

the end of the lever 2 showing the formation of the cam thereon.

In the construction shown in the drawings the device comprises a valve 1 and an operating lever 2 mounted on a supporting member or plate 3, the lever being adapted to be controlled by a magnet or motor 4 arranged to actuate an armature 5.

The valve 1 has the casing 6 thereof connected by means of a pipe 7 to the air system of the car or train, and is arranged so that when the valve member 8 is elevated it will bleed the air system and allow the brakes to become set. The stem 9 of the valve member 8 protrudes from the casing 6 into position to be engaged by the lever 2, the valve member being normally urged into such position by the spring 8.1.

The operating lever 2 may be of any suitable design, and is pivotally mounted on a stud 10 secured to the plate 3 below the valve stem 9. A weight 2.1 is adjustably mounted on the lever 2, by means of which the force of the lever may be controlled. An extension 13 is formed on the lever 2 which has the upper edge thereof, adjacent to its pivot, shaped to form a cam 11 which is adapted to engage the stem 9 for elevating the valve member 8. The cam 11 is spaced away from the valve stem 9 so that when the lever is first released it is permitted to obtain considerable momentum before striking the valve stem 9, whereby the first impulse of the lever against the valve stem 9 is in the nature of a blow. The other part 85 of the cam is first gradually inclined so that it has a tendency to pry the valve member 8 off from its seat, and then abruptly inclined as at 12, so that the valve member 8 will be 90 quickly moved to its wide open position after it has been pried from its seat. 95

The outer end of the extension 13 has a shoulder 14 formed thereon, which is adapted to be engaged by a coacting shoulder 15 formed on the upper end of the arm or catch 5. The catch 5 is supported on a spring 16, which normally urges it away from the magnet 4 into position to cause the engagement of the shoulders 14 and 15. The magnet 4 is connected by suitable conductors to a contact member (not shown) on the car, so as to be energized, upon the engagement of said contact with other contacts along the line, for the purpose of retracting the catch 5 to effect the release of the lever 2. A suitable 100 105 110

arrangement of such contacts is shown and described in my Patent No. 1,076,552 of Oct. 21, 1913.

In order to prevent the accidental release 5 of the lever 2, the catch 5 is locked in engagement with the extension 13 by means of a detent 17 pivotally mounted on the nut 18, which is screwed onto the stud 10 for securing the lever 2 thereon. The detent 17 is 10 provided with a shoulder 19, which is normally urged by gravity to rest upon and engage a shoulder 20 on the catch 5, as indicated in Fig. 1. A releasing arm or dog 21 is pivoted at 22 below the detent 17 and has 15 the upper or cam end thereof engaging the inclined edge 23 of the detent 17. A part 24 is attached to the lower end of the dog 21 and extends through the aperture 25 in the catch 5 and into closer proximity with the 20 pole of the magnet 4 than said catch. The dog 21, under the influence of the magnet 4, is adapted to elevate the detent 17, so as to permit the catch 5 to be retracted from engagement with the extension 13 of the lever 2. 25 As soon as the contacts on the car and along the road have passed out of engagement the catch 5 will be shifted toward its normal position. The detent 17 also will drop into its normal position and lock the 30 catch against being retracted. Therefore, the lever 2 can not be returned to its normal elevated position either manually or by reason of a recoil, unless the detent 17 is first lifted to release the catch 5 to permit it to 35 recede as the end of the extension 13 is brought in engagement with the inclined upper end of said catch.

The mechanism is placed in a suitable position on the car preferably out of the convenient reach of the engineer or operator, so that after the lever 2 is released it will have time to effect the setting of the brakes before the engineer can reset the mechanism. This insures the lapse of sufficient time to 45 permit the engineer to think and acquaint himself with the possibilities of danger ahead.

The operation of the device shown is as follows: When the mechanism is set, as shown 50 in Fig. 1, the air system may be operated in the usual manner with the ordinary control. If upon approaching a block or danger point where the contact on the car or engine is brought into engagement with the contact 55 along the track, and the circuit is completed through the magnet 4 by reason of the block being occupied or other obstructions to safety, the energization of the magnet 4 will attract the catch 5 and cause it to release the lever 2. In view of the closer proximity of the part 24 to the upper magnet 4, the dog 21 will be instantaneously actuated in advance of the catch 5, so as to cause the detent 17 to be elevated and disengage the shoulders 60 19 and 20. After the lever 2 has descended

a part of its throw and obtained some momentum the cam 11 will suddenly strike the valve stem 9, and as the gradually inclined part of the cam 11 approaches the stem 9 the valve member 8 will be pried from its seat. As the more abruptly inclined part 70 of the cam 11 approaches the stem 9, the valve will be rapidly opened to its full open position. The elevating of the valve member 8 opens communication between the air system and the atmosphere so that the air system is bled through the aperture 26 in the nipple 27. The rapidity with which the system will be bled may be regulated by the size 75 of the aperture 26.

When it is desired to reset the mechanism, it is necessary for the operator to elevate the lever 2, and at the same time elevate the gravity detent 17 to permit the reengagement 80 of the shoulders 14 and 15.

Although but one specific embodiment of this invention has been herein shown and described, it will be understood that some of the details of the construction shown may be altered or omitted without departing from 90 the spirit of this invention as defined by the following claims.

I claim:

1. A device of the class described, comprising a member mounted to swing up and down, a catch adapted to normally hold said member in its elevated position, a magnet arranged to actuate said catch for releasing said member, a detent adapted to lock said catch against accidentally releasing said member, and means adapted to be controlled by said magnet for retracting said detent to permit said catch to be actuated for releasing said member. 95

2. A device of the class described, comprising a fluid-pressure brake-controlling valve, mechanism adapted to normally urge said valve toward its open position, a catch adapted to hold said mechanism in its retracted position, a magnet arranged adjacent to said catch and adapted to actuate it so as to release said mechanism, a detent adapted to lock said catch against accidentally releasing said mechanism, and means adapted to be controlled by said magnet for 105 retracting said detent to permit said catch to be actuated for releasing said mechanism. 110

3. A device of the class described, comprising a fluid-pressure brake-controlling valve, a weighted lever pivotally mounted adjacent to said valve and adapted to normally urge said valve toward its open position, a catch adapted to hold said lever in its retracted position, a magnet arranged 120 in position to actuate said catch for releasing said mechanism, a gravity actuated detent adapted to normally engage said catch and lock it against accidentally releasing said lever, and means having a part thereof located between said catch and said magnet 125 130

and adapted to be controlled by said magnet for elevating said detent so as to permit said catch to be actuated for releasing said lever.

5 4. A device of the class described, comprising a supporting member, a fluid-pressure brake-controlling valve mounted on said member having the stem thereof extending below the casing, a weighted lever 10 pivoted below said stem, a catch adapted to hold said lever in its elevated position, a magnet arranged to actuate said catch to release said lever, a cam carried by said lever and having a part thereof spaced away 15 from said stem so as to permit of a movement of said lever before said cam engages said stem, said cam also having a gradually inclined portion adapted to have initial engagement with said stem so as to pry the 20 valve from its seat, and an abruptly inclined portion adapted to quickly move said valve to a wide open position after it has been pried from its seat.

5. A device of the class described, comprising a supporting member, a fluid-pressure brake-controlling valve mounted on said member and having the stem thereof protruding from the casing, a weighted lever pivotally mounted on said supporting 30 member, a cam surface on said lever adapted to engage said valve stem for opening said valve, an extension on said lever, a catch shiftably supported on said member and normally urged into position to engage 35 said extension for holding said lever in its elevated position, a magnet arranged adjacent to said catch and adapted to actuate the same for releasing said lever, a detent mounted on an axis coincident with the

axis of said lever and normally urged by 40 gravity to engage said catch so as to prevent the accidental release of said lever, a dog pivotally mounted below said detent and engaging the under side of said detent, and a part carried by said dog and located adjacent to said magnet in advance of said 45 catch, the under side of detent being inclined so that when said dog is actuated by said magnet said detent will be elevated so as to disengage said catch. 50

6. A device of the class described, comprising a supporting member, a fluid-pressure brake-controlling valve mounted on said member having the stem thereof extending below the casing, a weighted lever 55 pivoted below said stem, the pivot of said lever being located in alinement with said stem, a catch adapted to hold said lever in its elevated position, a magnet arranged to actuate said catch to release said lever, a 60 cam carried by said lever substantially concentrically of the pivot thereof and having a part thereof spaced away from said stem so as to permit of a movement of said lever before said cam engages said stem, said cam 65 also having a gradually inclined portion adapted to have initial engagement with said stem so as to pry the valve from its seat, and an abruptly inclined portion 70 adapted to quickly move said valve to a wide open position after it has been pried from its seat.

Signed at Chicago this 9th day of December, 1913.
